DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY.

MOTOR CONTROLLER.

Application filed November 19, 1924. Serial No. 750,734.

This invention relates to motor-controllers, more particularly of the graphite disk resistor type, and has for an object to provide such a controller with a simplified operating mechanism which is particularly adapted for knee-shift operation. Graphite disk rheostats are commonly constructed with a porcelain casing formed with a pair of wells each of which is filled with a stack 5 of the resistor elements or disks. Terminal screws in electrical contact with the end resistor elements are provided at one end of the porcelain casing, and a yielding bridging contact member is arranged at the other end 10 of the casing to be operated by some pressure exerting means such as an endwise movable rod passing through the casing. Movement of the rod causes the bridging contact member to first engage and gradually 15 press the resistor elements and thereby decrease their electrical resistance. The pressure exerting means has, in practice, only a limited motion and requires a rather stiff force or pull to operate it, particularly in the 20 latter stages of its resistor compressing motion. Considerable difficulty has been experienced in devising a satisfactory linkage of the requisite simplicity and compactness for operating such a rheostat in connection with 25 portable and cabinet sewing machine outfits for the control of the sewing machine motor.

In accordance with the present improvement, in its preferred embodiment, a bell-crank-lever is fulcrumed on the rheostat support and has one of its arms, which extends 30 transversely of the rheostat operating rod, apertured to receive the free end of such rod on which is screwed a head and lock-nut. An oscillatory shaft adapted to carry a knee-shift lever is journaled in a bearing boss on 35 the rheostat support in end-to-end relation, but not necessarily in alinement with the rheostat operating rod. This rock-shaft is connected to rock the bellcrank-lever, preferably by having fixed to its inner end an arm 40 formed with a cammed or inclined extremity which is engaged by the other arm of the bell-crank lever. A rocking movement of the operating shaft swings the bellcrank-lever and imparts the desired endwise movement to the rheostat operating rod.

In the accompanying drawings, Fig. 1 is a plan view of a sewing machine motor controller embodying the invention. Fig. 2 is a

longitudinal vertical section through the device. Fig. 3 is an end elevation, partly in section. Fig. 4 is a transverse section on the line 4—4, Fig. 1, and Fig. 5 is a perspective view of one of the operating elements of the controller-operating mechanism. 55

According to the preferred embodiments of the invention, as illustrated, 1 represents a supporting base for the rheostat 2 of the well known compression type. Such a rheostat commonly comprises a porcelain body 60 formed with a pair of wells 3 which are substantially filled with stacks 4 of resistor disks of carbon, graphite or the like. A terminal member 5 fitted with terminal screw 6 is provided at one end of each stack of disks 4 and a terminal pressure head 7 is provided at the opposite end of each of such stacks. Slidably mounted in the porcelain body is the rheostat operating rod 8, the headed end 9 of which carries the insulating bushing 10 which is surrounded by the spring 11. The rod 8 and bushing 10 pass through the resilient bridging member 12 and the stiffer backing member 13. Endwise movement of the rod 8 first carries the bridging member 12 into engagement with the terminal members 7, thus completing the circuit through the rheostat. Further movement of the rod 8 causes the member 12 to exert gradually increasing pressures upon 75 the stacks of resistor disks 4, thereby decreasing the electrical resistance of the rheostat. The spring 11 shifts the members 12, 13 and rod 8 toward open circuit position 80 when the pull-on the rod 8 is relieved. The rod 8 is threaded into an inverted T-shaped guide-block 14, Figs. 1 and 4, of insulating material, the horizontal arms of which slide in ways 15 in the porcelain body and hold the rod 8 against twisting; a lock-nut 16 being screwed tightly against the guide-block 14. Terminal elements 16, 17, constituting a short-circuiting switch, are connected 85 respectively to the terminal members 5 and are so arranged that the vertical arm 18 of the guide-block will press the terminal element 16 into contact with the terminal element 17 and short circuit the rheostat when the resistor disks are fully compressed. 90

Such a rheostat may be secured to the base 1 by screws 19 with its operating rod 8 in end-to-end relation with the rock-shaft 20 journaled in the boss 21 formed on the end 100

wall 22 rising from the base 1. The rock-shaft 20 has fixed thereon the collar 23 having a tooth 24 adapted to be engaged by the tooth 25 in the tubular hub end 26 of the 5 knee-shift lever 27; a knee-operated rheostat of this general character being disclosed, for example, in the U. S. patent to Hemleb, No. 1,444,917, of February 13, 1923.

The inner squared end 28 of the shaft 20 10 is fixed in a square hole in the operating arm 29, one end of which is preferably inclined at 30 so as to be eccentric to the shaft 20 and constitute a cam-edge. The arm 29 is formed beyond the cam-edge 30 with a 15 down-turned extremity 31' which is yieldingly held in engagement with the stop 32' on the base 1 by means of the spring 29^a which is connected at its upper end to the lateral projection 29^b on the arm 29 and 20 at its lower end is connected to the hook 29^c secured to the base 1. The other end 31 of the operating arm 29 is adapted to engage the stop 32 on the base 1.

Fulcrumed on the screw post 34 fixed to 25 the base 1 is a bellcrank-lever which may be made out of sheet-metal cut and bent to provide the cam-follower or power-arm 35, work-arm 36 and fulcrum-ears 37 through the apertures 38 of which the post 34 passes. 30 The power-arm 35 of the bellcrank-lever is preferably curved transversely of its length, as shown in Figs. 3 and 5; to form a rounded cam-engaging face 39. The work-arm 36 of the bellcrank-lever is longitudinally slotted at 40 to freely receive the rheostat operating rod 8 loosely surrounding which is a dished washer 41 which is engaged by the locked nuts 42 on the threaded extremity of the rod 8.

40 It will be readily understood that a limited turning movement imparted to the shaft 20 by the knee-shift lever 27 will, through the cam and bellcrank-lever mechanism, be converted into an effective pull exerted endwise 45 of the resistor compressing member or rod 8. The amount and degree of intensity of such pull may, of course, be altered by appropriate change in the shape or the amount of inclination of the cam-edge 30, or by changing 50 the lengths of the arms of the bellcrank-lever. This mechanism is found to act freely and without tendency to stick, cramp or bind. The requisite variations in pressure are easily imparted to the resistor-disk- 55 compressing member even in the latter stage of its resistance decreasing movement. It involves a minimum number of parts, is inexpensive to manufacture and is particularly useful in portable motor-driven sewing 60 machine outfits.

Having thus set forth the nature of the invention, what I claim herein is:—

1. The combination with a support and a compression rheostat mounted on said support and including an endwise movable oper-

ating rod, of a non-endwise movable rock-shaft journaled on said support in spaced end-to-end relation with said rod, the axes of said rod and rock-shaft being substantially parallel, and connecting mechanism for converting rocking movements of said shaft into endwise movements of said rod. 70

2. The combination with a rheostat having an endwise movable operating rod, of a rock-shaft disposed in end-to-end relation with such rod, the axes of said rod and rock-shaft being substantially parallel, a bellcrank-lever having one of its arms connected to said rod, an operating arm on said rock-shaft, and a connection between said operating arm and the other arm of said bellcrank-lever for swinging the latter. 75

3. The combination with a compression rheostat having an endwise movable operating rod, of a rock-shaft disposed in end-to-end relation with such rod, the axes of said rock-shaft and rod being substantially parallel, a bellcrank-lever having one of its arms connected to said rod, and a cam and follower connection between the other arm of the bellcrank-lever and said rock-shaft. 80

4. The combination with a compression rheostat having an endwise movable operating rod, of a rock-shaft disposed beyond one end of and extending substantially in the same direction as said rod, a cam on said rock-shaft, and a bellcrank-lever having one of its arms connected to said rod and the other of its arms positioned to be engaged by said cam. 95

5. The combination with a compression rheostat having an endwise movable operating pull-rod, of a rock-shaft disposed beyond one end of and extending substantially in the same direction as said rod, a cam secured to the end of said rock-shaft nearer said operating rod, a bellcrank-lever having one of its arms transverse to and connected to said rod, the other arm of said bellcrank extending in the same general direction as said rod and shaft and engaging said cam. 105

6. The combination of a base having at one end a wall at right angles to said base, with a compression rheostat mounted on said base and having an operating pull-rod parallel to said base and at right angles to said end-wall, a rock-shaft journaled transversely of and passing through said end-wall a cam on said rock-shaft within said end-wall, and a bellcrank-lever fulcrumed on said base and having one of its arms in engagement with said cam, the other arm of said bellcrank-lever being apertured to receive said pull-rod, and means on the end of said pull-rod constituting a head against which the bellcrank-lever is pressed to exert a pull on said rod. 115

In testimony whereof, I have signed my name to this specification.

DANIEL H. CHASON.
